(57) **CLAIM**

The ornamental design for a fluid control device as shown and described.

DESCRIPTION

FIG. 1 is a top front perspective view of a fluid control device;

FIG. 2 is a plan view of a top of the fluid control device shown in FIG. 1;

FIG. 3 is a plan view of a bottom of the fluid control device shown in FIG. 1;

FIG. 4 is an elevational view of a first side of the fluid control device shown in FIG. 1;

FIG. 5 is an elevational view of a second side of the fluid control device shown in FIG. 1;

FIG. 6 is an elevational view of a third side of the fluid control device shown in FIG. 1;

FIG. 7 is an elevational view of a fourth side of the fluid control device shown in FIG. 1;

FIG. 8 is a cross-sectional view taken in the direction of line 8-8 in FIG. 5; and,

FIG. 9 is a cross-sectional view taken in the direction of line 9-9 in FIG. 7.

The broken lines and unshaded surfaces depict portions of the fluid control device that form no part of the claimed design.

1 Claim, 9 Drawing Sheets
